FIG. 3.

FIG. 4.

Inventor

William H. Branston,

By his Attorneys

Edgar V. Tate & Co.

UNITED STATES PATENT OFFICE.

WILLIAM H. BRANSTON, OF BROOKLYN, NEW YORK, ASSIGNOR OF ONE-HALF TO
BERNARD BOYLE, OF CORONA, NEW YORK.

CHIMNEY.

Application filed August 31, 1920. Serial No. 407,074.

To all whom it may concern:

Be it known that I, WILLIAM H. BRANSTON, a citizen of the United States, and residing at Brooklyn, in the county of Kings 5 and State of New York, have invented certain new and useful Improvements in Chimneys, of which the following is a specification, such as will enable those skilled in the art to which it appertains to make and use 10 the same.

This invention relates to chimneys and particularly to chimney top structures, and the object thereof is to provide an improved device of this class which is preferably made 15 complete of concrete or similar material, and which may be used in the place of, or as a substitute for ordinary chimney tops, built up of bricks or similar material and forming a continuation of or outlet for the 20 flues or chimney structures in the walls of houses of various kinds and classes, a further object being to provide a chimney top structure of the class described which may be mounted on or used in connection 25 with a plurality of flues or chimney structures arranged side by side or in close proximity in the walls of buildings; a still further object being to provide a structure of the class described which may be used in the 30 manner above set out and which will operate to prevent back drafts and cause a steady and continuous draft at all times and under varying weather conditions.

The invention is fully disclosed in the following specification, of which the accompanying drawing forms a part, in which the separate parts of my improvement are designated by suitable reference characters in each of the views, and in which:—

40 Fig. 1 is a central longitudinal vertical section of my improved chimney or chimney structure;

Fig. 2 a top plan view thereof;

Fig. 3 a bottom plan view; and,

45 Fig. 4 a side view thereof.

In the practice of my invention I provide a chimney top structure *a* of the class specified which is made in the form shown of concrete and preferably integral and is approximately rectangular in form and oblong 50 in cross section, and comprises a bottom or base portion *b* and an enlarged top portion *c*, the enlargement being in the direction of the narrower sides of the bottom or base 55 portion, or in the direction of the greatest

transverse dimensions of said bottom or base portion.

In the top of the chimney top structure is a central opening *d*, the opposite side walls of which, in the direction of the greatest 60 dimensions of the bottom or base portion are curved inwardly and downwardly as shown at *e* in such manner that the bottom 65 *f* of the opening *d* is much smaller than the top of said opening.

The narrower sides *g* of the top of the chimney top structure are also inclined downwardly and in the top portion of the narrower sides thereof and just below the top are openings *h*, the side walls of which 70 are inclined inwardly and downwardly.

In the central portion of the chimney top structure is a V-shaped transverse body and partition portion *i*, the side walls *j* of which divide the bottom or base portion thereof 75 into two separate side passages *k*, which are narrower at the top than at the bottom, and the body portion *i* is provided centrally of the top with a raised vane or partition member *m* which preferably extends about two-thirds 80 of the distance to the top opening *d*, and which divides the bottom portion of said opening into separate side passages *n*, and said body portion *i* is also provided at the top thereof with outwardly directed vanes 85 or partition members *o* which extend into the top portions of the side passages *k*, which open outwardly at *h*, and this construction forms in the top of the partition body *i* transverse curved recesses *p*. 90

With this construction the opening *d* in the top of the device is extended downwardly and inwardly by the parts *e* and divided into two passage-ways by the part *m* of the central member *j*, and the laterally directed 95 openings *h* also communicate with the passage-ways, the inner end portions of which are divided by the parts *o* of the central member, which open outwardly and laterally to the openings *h* and said central member 100 is provided with a downwardly directed portion which divides the bottom part of the device into two passage-ways which communicate with the opening at the bottom of said device and all of said passage-ways are in 105 communication; and when the chimney top structure is in use the heated gases from the flues pass upwardly through the device in the direction of the arrows *x* and out through the top side openings *h*, as indicated 110

by the arrows x^2 and the currents of air which enter the top opening d are also diverted and passed downwardly and outwardly through the side openings h , and this causes a continuous draft through the flues in the walls of a building and through the chimney top structure under various conditions of weather and also prevents any back draft through the top structure and through 10 said flues when the wind is blowing.

Although I have described my improved chimney top structure as composed of concrete, and preferably formed integrally, I may, in the construction thereof, divide said 15 structure horizontally into separate parts, preferably along the dotted line $y-y$ of Fig. 1 in order to facilitate and cheapen the process of manufacture but, in this event, the separate parts would be cemented together 20 or otherwise connected so as to make the complete device of substantially integral construction.

My invention is not limited to the exact form or shapes and the comparative dimensions of the various parts thereof, herein 25 shown and described, and changes therein and modifications thereof may be made, within the scope of the appended claims, without departing from the spirit of my invention or sacrificing its advantages, and while I have shown and described my improved chimney structure as of approximately 30 rectangular form in horizontal section, my invention is not limited to this exact 35 shape, and the said chimney or chimney structure may be made circular or oval, or of any other desired shape in horizontal section.

It will also be understood that while I 40 have described the chimney as being preferably composed of concrete, the same may be composed of, or formed from any desired and suitable material.

Having fully described my invention, 45 what I claim as new and desire to secure by Letters Patent, is:—

1. A chimney structure of the class described comprising a hollow body portion open at the top and bottom and at the top 50 of the opposite sides, all of said openings being in communication and a transverse division body mounted in the body portion

approximately centrally thereof and adapted to sub-divide the communications between the top and bottom openings and said side 55 openings, said transverse division body being approximately V-shaped in form and provided with an upwardly directed vane located centrally of the top opening, and means subdividing the communications between said side openings and said top opening.

2. A chimney top structure composed of a hollow body portion open at the bottom and provided centrally of the top thereof with an 65 opening and in the top of the opposite sides with other openings, all of which communicate with the interior of said body portion and a central partition member within said body portion and having parts which divide 70 said openings into separate passages.

3. A chimney top structure composed of a hollow body portion open at the bottom and provided centrally of the top thereof with an 75 opening and in the top of the opposite sides with other openings, all of which communicate with the interior of said body portion and a central partition member within said body portion and having parts which divide 80 said openings into separate passages, all of said passages being in communication.

4. A chimney top structure of the class described comprising a hollow body portion open at the top and bottom and the opposite sides of which are also provided at the 85 top with openings, all of said openings communicating with the interior of the body portion, and a central partition member having upwardly, and laterally and upwardly directed parts which divide the top and side 90 openings into separate passages, said central partition member being also provided with a part which extends downwardly and divides the bottom opening into separate 95 passages.

In testimony that I claim the foregoing as my invention I have signed my name in presence of the subscribing witnesses this 28th day of August 1920.

WILLIAM H. BRANSTON.
